UNITED STATES PATENT OFFICE.

JOHN A. GROSHON, OF NEW YORK, N. Y.

ELEVATOR.

SPECIFICATION forming part of Letters Patent No. 224,900, dated February 24, 1880.

Application filed December 29, 1879.

To all whom it may concern:

Be it known that I, JOHN A. GROSHON, of New York, in the county of New York and State of New York, have invented a new and 5 useful Improvement in Elevators, of which the following is a specification, reference being had to the accompanying drawings.

The invention relates to an improvement in elevators; and it consists in the construction 10 and arrangement of a steam-cylinder and secondary water-cylinder, with their pistons and connections, and gearing for controlling the operation of the said cylinders, as hereinafter fully described.

15 Referring to the accompanying drawings, Figure 1 is a central vertical longitudinal section of the invention. Fig. 2 is a top view of same.

20 A indicates the steam-cylinder, having a piston, *a*, and B the secondary or water cylinder, supplied with the piston *b*. The cylinders A B are mounted horizontally, so that their longitudinal centers are on the same plane, and are separated a given distance by the guide- 25 rods D, which extend from the inner head of one cylinder to that of the other, and serve as a trainway for the carriage *d*, hereinafter described.

20 The pistons *a b* are connected by the piston- rods E, which are of suitable length to insure the proper working of the pistons, and pass out through the head of one cylinder into that of the other. The pistons *a b* are connected, in the present instance, by two rods, E, which 35 are on the same horizontal plane, and connect with the pistons on either side of the centers of same. This construction is preferred not only because it renders the machinery more durable, but also because it insures a more 40 regular and even movement of the pistons.

45 The rods E, between the cylinders A B, are protected by the guide-rods D, and at a suitable point are rigidly secured to the carriage *d*. Thus when the rods E and pistons *a b* are moved either toward or from the rear of the cylinders the carriage *d* will have a corresponding movement. Upon the ends of the carriage *d* are mounted the pulley-wheels *e*, over which and the similar wheels *f* passes 50 the rope F, by which the elevator-car is either raised or lowered.

When the carriage *d* is forced toward the water-cylinder it draws the rope F and causes the car to ascend; and when this movement of the carriage is reversed the rope is slack- 55 ened and the car permitted to descend.

Above, and connected with the cylinders A B, are the chests H I, containing the balance-valves *h i*, which latter are connected and in their movement controlled by the rod K. Up- 60 on the rod K, at about its center, is secured the rack *l*, which meshes with the pinion L, mounted upon one end of the shaft M, upon the other end of which is secured an actuating - wheel, *m*. Thus whenever this latter 65 wheel is rotated either to the right or left it imparts a similar movement to the pinion L, which then forces the rod K and the balance- valves *h i* either forward or backward, controlling the entrance of steam and water, re- 70 spectively, to the cylinders A B and the entire operation of the machine. The balance- valves *h i* are supplied with a central bore, and the valve *i* also with the apertures *n*, which lead from the central bore through the wall of 75 the valve.

The chest I is connected with the water-cylinder B at its inner end by the port N, and at its outer end by the pipe P, which passes from the end of the said chest and enters the upper 80 part of the cylinder B adjacent to its outer end. Thus when the piston *b* is moved toward the outer end of the cylinder B, the balance- valve being properly adjusted, the water passes up through the pipe P, thence into 85 the chest I and valve *i*, and out through the apertures *n*, and down through the port N into the cylinder B again, on the opposite side of the piston *b*, which, when its movement is reversed, causes the water to return up through 90 the port N, the valve *i*, and down into the cylinder again through the pipe P.

The chest H is connected with the steam- cylinder A at the forward end of the latter by the port *p*, and at the inner end by the port *t*, 95 and is supplied with a proper exhaust and a port whereby steam is admitted.

When it is desired to cause the elevator-car to ascend the balance-valves *h i* are moved by the rack *l* and pinion L to open the port *p* and 100 the port N. Through the former then passes into the cylinder A the steam, which forces

the piston *a*, the rods *E*, carriage *d*, and piston *b* toward the rear end of the cylinders. This movement forces the water in the cylinder *B* up through the pipe *P*, and then through 5 the chest *I* and port *N* into the front end of the cylinder, as aforesaid, and also causes the rope *F* to be drawn upon the wheels *f*, elevating the car. The car may be stopped at any point by simply moving the balance-valve 10 *h* over the port *p* by operating the pinion *L*. To set the car in motion again it is only necessary to open the said port *p* by reversing this last movement of the pinion *L*.

When it is desired to lower the elevator-car 15 the valve *h* is moved simply enough to open the port *t*, when the steam will enter on the opposite side of the piston *a*, and force it, with the rods *E*, carriage *d*, and piston *b*, to their former position, slackening the rope *F* and 20 permitting the car to descend. During this movement the water in the cylinder *B* is forced up through the port *N*, the valve *i*, and pipe *P*, and then down into the cylinder *B* at its rear end, as before described.

25 If desired, in lieu of employing the pipe *P*, I may make a direct connection between the chest and cylinder by forming a port, *x*, as shown in dotted lines in Fig. 1.

The operation above set forth shows one 30 method in which the invention may be successfully practiced; but I am enabled by a slight modification to present a construction of equal utility, which I will now proceed to describe.

35 In this modified form I dispense with the pipe *P* and the port *p*, and in lieu of the pipe *P*, I employ a pipe, *T*, which passes from the rear end of the chest *I* to a suitable reservoir or tank, *V*. In this instance, when it is de- 40 sired to elevate the car the port *N* is opened. This allows the water from the tank *V* and pipe *T* to pass through the valve *i* and port *N* into the cylinder *B* in front of the piston *b*, forcing it rearward, which movement draws the rods *E*, carriage *d*, piston *a*, and rope *F* also 45 toward the rear, elevating the car. The car may be stopped at any point by simply closing the port *N*, and started again by opening it. When the car is to be lowered, if the 50 weight in it is not sufficient to overcome the force of the water and drive it back into the tank *V*, steam may be admitted to the cylinder *A* through the port *t*. This will force the piston *a* and its connections toward the front 55 of the machine, driving the water into the pipe *T* and tank *V* through the port *N* and valve *i* and lowering the elevator-car.

I propose, in the operation of the elevator, to apply a suitable governor to the valves *h i*, which will be actuated by the speed of the car 60 to open or close, partially or wholly, the ports admitting the steam and water to the cylinders, and thus cause the said car to have a regular and even movement. This governor, in connection with a novel form of valve, I 65 intend to make the subject of a separate application for patent.

What I claim as my invention, and desire to secure by Letters Patent, is—

1. The cylinders *A B*, having suitable ports, 70 and the pistons *a b*, connected by rods, in combination with suitable valves for controlling said ports, said valves being connected by a rod, *K*, operated by a rack and pinion, substantially as set forth.

2. In combination with the cylinders *A B*, having suitable pistons and ports, the valves *h i*, connected by the rod *K*, operated by a rack and pinion, substantially as set forth. 75

3. The cylinders *A B*, having pistons *a b* 80 and rod or rods *E*, the former cylinder being supplied with the ports *p t*, and the latter with the port *N* and pipe *P*, in combination, with the hollow balance-valves *h i*, rod *K*, rack *l*, and pinion *L*, substantially as set forth. 85

4. The cylinders *A B*, properly supplied 90 with pistons and ports, in combination with the hollow balance-valves *h i*, the latter being supplied with the apertures *n*, substantially as specified.

5. The combination of the cylinders *A B*, having suitable ports and pistons connected 95 by the rod or rods *E*, driving the carriage *d*, with the hollow balance-valves *h i*, connected by a rod, *K*, operated by a rack and pinion, substantially as described.

6. The cylinders *A B*, having, respectively, the port *t* and the port *N*, and supplied with pistons connected by the rod or rods *E*, driving the carriage *d*, in combination with the 100 balance-valves *h i*, connected and operated by a rod, *K*, and with the pipe *T* and tank *V*, substantially as set forth.

In testimony that I claim the foregoing improvement in elevators, as above described, I 105 have hereunto set my hand this 20th day of December, 1879.

JOHN A. GROSHON.
